(57) **CLAIM**

The ornamental design for a popcorn popper, as shown and described.

DESCRIPTION

FIG. 1 is a perspective view of a popcorn popper lid assembly;

FIG. 2 is an elevation view of a top of the lid assembly shown in FIG. 1;

FIG. 3 is an elevation view of a bottom of the lid assembly shown in FIG. 1;

FIG. 4 is an elevation view of a first end of the lid assembly shown in FIG. 1;

FIG. 5 is an elevation view of a second end of the lid assembly shown in FIG. 1;

FIG. 6 is an elevation view of a first side of the lid assembly shown in FIG. 1;

FIG. 7 is an elevation view of a second side of the lid assembly shown in FIG. 1;

FIG. 8 is a perspective view of the lid assembly shown in FIG. 1 coupled to an example of a vessel;

FIG. 9 is a perspective view of a popcorn popper lid assembly;

FIG. 10 is an elevation view of a top of the lid assembly shown in FIG. 9;

FIG. 11 is an elevation view of a bottom of the lid assembly shown in FIG. 9;

FIG. 12 is an elevation view of a first end of the lid assembly shown in FIG. 9;

FIG. 13 is an elevation view of a second end of the lid assembly shown in FIG. 9;

FIG. 14 is an elevation view of a first side of the lid assembly shown in FIG. 9; and,

(Continued)

FIG. 15 is an elevation view of a second side of the lid assembly shown in FIG. 9. The broken lines shown in the drawings illustrate portions of the popcorn popper and form no part of the claimed design.
